(57) **CLAIM**

The ornamental design for an old print tray with corks, as shown and described.

DESCRIPTION

FIG. 1 is a perspective view of an old print tray with corks, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention; and,

FIG. 6 is a top plan view of the invention, the bottom plan view being a mirror image thereof.

The pattern of corks illustrated in the drawings can vary based on the user's preference. Thus, the particular configuration shown is just one configuration of corks possible of many.
